UNITED STATES PATENT OFFICE

2,476,080

SMOKER'S PIPE WITH ADJUSTABLE TUBE

Harold Brown, Flushing, N. Y.

Application November 9, 1944, Serial No. 562,584

7 Claims. (Cl. 131—212)

1

My invention relates to smoker's pipes, and has for its main object to provide a pipe for smoking tobacco which will eliminate certain well known drawbacks of the present pipes.

As it is known, the smoker's pipes used to-day, have a bowl which is filled with tobacco, the top of the tobacco is ignited, and the filling gradually smoked. It is obvious that in this manner, the smoke has to pass through all the tobacco yet unconsumed and laying underneath the burning region or strata, and it is also well known that the smoke passing through the yet unconsumed tobacco will deposit various harmful materials, vapors, etc., so that the tobacco will become wet, soggy, saturated with various materials, and when burned in such a condition, it will produce an unpleasant and even harmful smoke, and, certainly, the tobacco so contaminated and then smoked, will lose its original fresh taste and aroma.

My invention aims to provide means in a smoker's pipe whereby the tobacco will be burned and consumed in successive layers or strata, and the smoke from each layer or region will be directly drawn into and through the stem of the pipe without first passing through the unconsumed portion of the tobacco. I am aware of the fact that many devices have been proposed for such a purpose, but, to my knowledge, experience and information, none of these devices were practical, efficient, and desirable, and none of them found their way into actual practice and use.

The main purpose of my invention is to provide a pipe for smoking tobacco, in which the tobacco will be consumed in successive layers, in any desired number, or plurality of stages, without the smoke ever passing through the unconsumed part of the tobacco.

Another object of my invention is to provide means whereby the smoking of the tobacco may be stopped at any stage of the consumption thereof, and the pipe caused to automatically stop operating.

Still a further object of my invention is to provide a smoker's pipe, as characterized hereinbefore, in which the smoke will have to pass through quite a complicated devious way, where it will have a chance and means for depositing condensates, vapors, and other harmful ingredients, and wherein it may also be cooled.

Still further objects of my invention will be apparent as the specification of the same proceeds, and, among others, I may mention: to provide a device of the character indicated, which will be simple in construction, easy to operate

2

and use, will be applicable to pipes used at present, and which may be conveniently removed from the pipe, the same being adapted to be disassembled, cleaned, and just as easily and conveniently replaced into the pipe.

With the above objects in view, my device mainly consists in an upstanding tube placed into the bowl of the pipe, being open at the top, so that the smoke of the burning tobacco may be drawn through the tube without touching the rest of the tobacco underneath the burning region, said tube being slideable downwardly, and thereby causing gradual layers or strata of the tobacco to be burned.

15 In addition, said tube may be arranged in a self containing unit, easily applied to any pipe, or removed therefrom in order to take apart and clean the same, and just as easily assembled and returned into the pipe, means being provided in 20 said device containing said tube, whereby the smoke is caused to pass through a complicated passageway, which possibly may include receivers or containers for condensates or other deposits, and for cooling the smoke.

25 In the drawings forming a part of this specification and accompanying the same:

Fig. 1 is a fragmentary sectional elevation showing the bowl of a pipe constructed according to my invention;

30 Fig. 2 is another sectional view, the section being taken on the line 2—2 of Fig. 1.

Fig. 3 is another fragmentary sectional view taken on the line 3—3 of Fig. 1;

35 Fig. 4 is a longitudinal sectional view of a modified embodiment of my invention;

Fig. 5 is a cross sectional view thereof, the section being taken on the line 5—5 of Fig. 4.

Referring now to the drawings more in detail by characters of reference, the numeral 10 40 indicates my novel pipe, in general, having a bowl 11, and the stem 12, and, obviously, made of any appropriate material, like wood.

The bowl and stem of the pipe may be of any design and construction, entirely as it is 45 usual now, so that my pipe not only may be newly manufactured, but any old pipe may be changed to my novel construction, as will be obvious from the description herein to follow.

In exercising my invention, a screw threaded 50 bore 13 will be made through the bottom of the bowl 11 of the pipe shown in Figs. 1, 2 and 3, and a screw threaded plug 14 secured therein by the cooperation of their threads, said plug preferably being made of metal, but it can be 55 made of any other appropriate material, as will

be obvious. A central sleeve 15 is provided in the plug member 14, having the aperture or opening 16 therethrough, and a tube or pipe 17, also preferably made of metal, may be pushed into the upper end of said opening 16, the major portion of said tube 17 projecting upwardly in the center of the pipe bowl 11. Tube 17 may be closed at the top 18 and said top may be conical, as indicated in Fig. 1. Apertures or smoke inlet holes 19 are provided around the tube 17 near its top.

The plug member 14 may have a depending exteriorly threaded tubular, or hollow cylindrical, downward extension 20, and an appropriately and attractively shaped hollow condensation receiver, and smoke cooler, 21 may be secured on the depending sleeve 20 by its interiorly screw threaded upper hollow cylindrical extension 22.

An exteriorly screw threaded inner tube 23 is threaded into the lower part of the tube 17, its lower end passing through a bore 24 in the center of the bottom of the combustion and cooler container 21, and terminating in the knurled disk or knob 25, by which it may be rotated in said bore or aperture 24.

Means may be provided to prevent an upward or downward movement of the inner tube 23 and permit only its rotation, and, as an example of such means, a collar 26 is shown, secured on the inner tube 23 right above the bottom of the condenser container 21.

A plurality of smoke exit apertures or holes 27 are provided around the lower part of the inner tube 23 near the bottom of the container 21. The plug 14 may also have a ring shaped inner hollow space 28 which will communicate with the bore 29 of the stem of the pipe, as by the opening 30 in the outer wall of the plug 14, registering with the bore 29.

The use and operation of my device will be obvious from the above description, but I want to offer the following further explanations and remarks: When it is desired to fill the pipe, the knurled knob 25 at the bottom of my device, will be rotated in an appropriate direction thereby causing the outer tube 17 to move upwardly, as indicated by the arrow 31, until its upper openings 19, provided for the intake of the smoke, will be at a desired height, whereupon the pipe bowl will be filled with tobacco, as indicated at 32, just covering the top 18 of the tube 17. The tobacco will be lit and the pipe smoked through the stem 12, as usual. The preferred method, however, would be to have the tube 17 in its lowest position, fill the bowl of the pipe, then move the tube upwardly through the tobacco. This will be facilitated by the pointed top of the tube.

It will be seen that only the top layer 33 of the tobacco will burn, and the smoke from the stem almost immediately will be drawn through the openings 19 into the tube 17, as indicated by the arrow 34. The smoke then will go downwardly through the tube 17, then through the inner tube 23, will exit through the lower openings 27, as indicated by the arrow 35, will go up into the hollow ring space 28 in the plug 14, and will exit into the bore 29 of the stem 12, through the opening 30, as indicated by the arrow 36.

It will be seen that not only will all the smoke be drawn directly from the top burning region 33, but the smoke will almost immediately enter the inside of the tube and will avoid all the fresh tobacco underneath the burning layer or region, whereupon the smoke will pass through the hollow tube downwardly, will exit through the

apertures or holes 27 in the bottom of the inner tube 23 (arrow 35), will pass upwardly through the vessel 21, depositing most of its condensation products, vapors, etc., in said vessel or container, then pass upwardly into the hollow ring space 28 in the plug 14 (arrow 37), and then through the opening 30 into the bore 29 of the stem 12, as usual, and as indicated by the arrow 36.

It will be seen that not only will all the smoke be drawn from the burning region directly into the tube 17, but the smoke will pass through a long, devious passage, having ample chance to deposit all the harmful ingredients therein, and will have ample opportunity to be cooled, thereby my pipe produces a cool, harmless smoke, which, however, will retain all the fresh aroma of the tobacco without being contaminated by vapors, condensations, and deposits of earlier smokes, as is the case with the ordinary pipes used today.

After the region or layer 33 is consumed, the burning of the tobacco is stopped if no adjustment is made, so that my pipe will stop burning at any desired point. If it is to be smoked through, then the knob 25 will be rotated in the opposite direction to that used when raising the tube whereby the interaction of the screw threaded tubes 23 and 17 will cause the tube 17 to move downwardly a desired distance, as indicated by the arrow 38. After moving the tube a predetermined distance, the smoking may be continued and a second layer, let us say the one indicated by the numeral 39, will be consumed, and its smoke, again, will be drawn directly through the apertures 19 into the tube 17. By a gradual lowering of the tube 17, the tobacco in the bowl of the pipe may be consumed in as many regions, layers, or stages, as desired, until the apertures 19 of the outer tube will arrive to the bottom of the bowl 11, when, of course, all the tobacco in the bowl will have been burned.

It also will be seen that at no point or stage 45 of the consuming of the tobacco in the bowl 11, will any smoke pass through any of the lower tobacco, so that all of the smoke will be produced by fresh tobacco and will have its desired aroma and taste without being contaminated by the harmful deposits and condensations mentioned hereinbefore and well known to pipe smokers.

It also will be obvious that my construction lends itself to easy operation and adjustment, all its parts will be simple and reliable, and there 55 will be no possibility, and not even any tendency, for any smoke deposit or condensation to escape from it, or to pass through any other way than the one described.

It also will be seen that my device may easily be installed into any existing pipe by simply preparing a screw threaded bore 13 at the bottom thereof adapted to receive the screw threaded plug 14 of my device, and that my device may be as easily removed from the pipe by unscrewing the plug 14. The elements or parts of my device may then be taken apart by a few unscrewing steps, whereupon the bowl of the pipe and each part of my device may be thoroughly cleaned, the parts restored to their position in the device, and the whole device replaced in the bore 13 of the bowl of the pipe.

In Figs. 4 and 5 I show another embodiment of my invention. In this embodiment, also, the numeral 10 represents the pipe, in general, having the bowl 11 and the stem 12, with a bore 29.

A plug 40, generally similar to the plug 14, described in the earlier embodiment, may be secured in a bore 41 in the bottom of the bowl, by any appropriate method, as by the screw threads 42.

The plug 40, in this case also, may have a depending hollow cylindrical portion 43 with exterior screw threads 44 on which may be secured a cooling and condensation receiving container 45, as by the interior screw threads 46 at its top portion. The plug 40 may have a similar smoke exit opening 30 as described hereinbefore communicating with the bore 29.

In this embodiment, my invention includes a tube or pipe 47 having a preferably conical pointed closed top 48, and a plurality of openings 49, for drawing the smoke from the burning tobacco into the tube, as has been described hereinbefore. The tube may slide upwardly or downwardly, in a sealing manner, in an aperture 50 in the plug 40, and its lower portion 51 will extend into the space within the hollow plug 43 and the container 45.

A disk 52 may be secured on the lower portion 51 of the tube 47, said disk having exterior screw threads 53. A wider tube or hollow cylinder 54 may rise from the bottom of the container 45, having the interior screw threads 55 meshing with the screw threads on the disk 52.

A rotatable member 56 may be arranged in the bottom of the container 45, having a knurled operating disk portion 57, by which it may be rotated, as will be obvious. Two upstanding rods 58 are secured on the member 56 passing through appropriate holes 59 in the disk 52.

It will be seen that when the knurled knob 57 is rotated in an appropriate direction, it will rotate the disk 52 in the same direction, whereby the disk will move downwardly, as indicated by the arrow 60, through the operation of the screw threads 53 and 55, and will draw the tube 47 in a downward direction to a desired extent.

The smoke will enter through the apertures 49, as indicated by the arrows 61, will pass downwardly through the tube 47 into the wider tube or hollow cylinder 54, from which it will exit into the container 45 through a plurality of openings or apertures 62, as indicated by arrows 63, after which the smoke will find its way to the exit opening 30 (arrow 64).

In this embodiment, obviously, the tube 47 may be made much narrower than the outer tube 17 in the earlier modification. It also will be obvious that a pipe constructed according to said second modification will be easily taken apart and again assembled, similarly as described in connection with the first form of my invention.

In the first embodiment of my invention, at 70, (Figs. 1 and 3), a pin and slot engagement is shown between the pipe 17 and the plug 14, whereby rotation of the pipe is prevented, as will be obvious.

In the second modification, Figs. 4 and 5, the numeral 71 indicates two downwardly projecting pins on the bottom of the disk 52. The purpose of these pins is to provide a limit for the downward movement of the disk whereby the disk must stop at a predetermined distance above the rotating member 56 in the lowest position, so that even in that position, free passage is provided for the smoke to exit through the opening 63.

While I have shown preferred embodiments of my invention, it is to be understood that changes and variations may be resorted to in the elements,

construction or use of my invention, and I reserve my rights to such changes, variations and uses as are within the spirit of this specification and the scope of the claims hereunto appended.

5. What I claim as new and want to protect by Letters Patent of the United States, is:

1. In a smoker's pipe, having a bowl for the tobacco to be consumed, and a stem with a bore communicating with the bowl wherethrough to draw the smoke of the tobacco, in combination, a tube projecting upwardly in said bowl, only the upper end of the tube communicating with the bowl to draw the smoke through said opening into the tube from the zone of the burning tobacco, means to move the tube downwardly to cause successive layers of tobacco to be burned, and communicating means between the interior of the tube and said bore in the stem, for the exit of the smoke.

2. In a smoker's pipe, as set forth in claim 1, said tube being adapted to slide through the bottom of the bowl, and said communicating means between the tube and the bore of the stem including a container adapted to receive deposits from the smoke and to cool the smoke.

3. In a smoker's pipe, having a bowl, a stem, and a bore in the stem for the smoke, in combination, a hollow removable plug in the bottom of the bowl, a first tube projecting from said plug upwardly into said bowl, and being sealingly slideable in said plug, and a deposit container secured on said plug communicating with the space therein, a second tube rotatably secured in said container, and projecting into said first tube, communicating screw threads on said two tubes, means to prevent axial movement of said second tube, means at the upper end of the first tube for communicating with the interior of the pipe bowl, means at the lower end of said second tube communication with said container, and means for communication between the space in said hollow plug and the bore in the stem of the pipe.

4. In a smoker's pipe, having a bowl for the tobacco to be consumed, and a stem with a bore communicating with the bowl wherethrough to draw the smoke of the tobacco in combination, a tube projecting upwardly in said bowl, only the upper end of the tube communicating with the bowl to draw the smoke through said opening into the tube from the zone of the burning tobacco, means to move the tube downwardly to cause successive layers of tobacco to be burned, communicating means between the interior of the tube and said bore in the stem, for the exit of the smoke, a second tube inserted into said first tube, and means to stationarily secure said second tube and prevent its axial movement, said first tube being axially movable on said second tube, and said means for communication between the interior of the first tube and the bore of the stem including said second tube.

5. In a smoker's pipe, having a bowl for the tobacco to be consumed, and a stem with a bore communicating with the bowl wherethrough to draw the smoke of the tobacco, in combination, a tube projecting inwardly in said bowl, only the upper end of the tube communicating with the bowl to draw the smoke through said opening into the tube from the zone of the burning tobacco, means to move the tube downwardly to cause successive layers of tobacco to be burned, and communicating means between the interior of the tube and said bore in the stem, for the exit of the smoke, a second tube inserted into said first tube means to relatively stationarily secure

said second tube and prevent its axial movement, said first tube being axially movable on said second tube, and said means for communication between the interior of the first tube and the bore of the stem including said second tube, said second tube being rotatable, and said means to cause said first tube to slide downwardly including cooperative elements between said two tubes operable upon the rotation of said second tube.

6. In a smoker's pipe, having a bowl for the tobacco to be consumed, and a stem with a bore communicating with the bowl wherethrough to draw the smoke of the tobacco, in combination, a tube projecting inwardly in said bowl, only the upper end of the tube communicating with the bowl to draw the smoke through said opening into the tube from the zone of the burning tobacco, means to move the tube downwardly to cause successive layers of tobacco to be burned, and communicating means between the interior of the tube and said bore in the stem, for the exit of the smoke, a second tube inserted into said first tube, means to relatively stationarily secure said second tube and prevent its axial movement, said first tube being axially movable on said second tube, said means for communication between the interior of the first tube and the bore of the stem including said second tube, said second tube being rotatable, said means to cause said first tube to slide downwardly including cooperative elements between said two tubes operable upon the rotation of said second tube, and a container for the deposits of the smoke secured to the bottom of the bowl, said second tube being secured in said con-

tainer, and said means to communicate between the bowl of the pipe and the bore in the stem including said container.

5. In a smoker's pipe, having a bowl for the tobacco to be consumed, and a stem with a bore communicating with the bowl wherethrough to draw the smoke of the tobacco, in combination, a tube projecting inwardly in said bowl, only the upper end of the tube communicating with the bowl to draw the smoke through said opening into the tube from the zone of the burning tobacco, means to move the tube downwardly to cause successive layers of tobacco to be burned, communicating means between the interior of the tube and said bore in the stem, for the exit of the smoke, and a removable plug in the bottom of the bowl, said means to move the tube, and said communicating means being carried by said removable plug.

HAROLD BROWN.
